FISHING POLE HOLDER

Harold Erickson, 1455 McAllister Ave.,
Sacramento, Calif. 95822

Filed May 25, 1970, Ser. No. 23,136

Term of patent 14 years

Int. Cl. D22—08

U.S. Cl. D22—22

FIG. 1 is a rear elevational view of a fishing pole holder, showing my new design, with the bail in lowered position;

FIG. 2 is a side elevational view of FIG. 1;

FIG. 3 is a side elevational view of the other side, with the bail in elevated position;

FIG. 4 is a front elevational view of FIG. 3;

FIG. 5 is a front elevational view showing the bifurcated pole rest, the ground anchor and the bail in folded position;

FIG. 6 is a sectional view of the ground anchor and bail pivot on the line 6—6 in FIG. 4;

FIG. 7 is a sectional view of the ground anchor on the line 7—7 in FIG. 4; and

FIG. 8 is a sectional view of the ground anchor on the line 8—8 in FIG. 4.

I claim:

The ornamental design for a fishing pole holder, as shown and described.
